(57) **CLAIM**

The ornamental design for lockable L-handle, as shown and
described.

DESCRIPTION

FIG. 1 is a front perspective right perspective view of the
lockable L-handle of the invention, shown in its lockable
position.

FIG. 2 is a front perspective right perspective view of the
lockable L-handle of the invention, shown with its grip
handle moved out of the lockable position.

FIG. 3 is a front view of the lockable L-handle of FIG. 1;
FIG. 4 is a rear view of the lockable L-handle of FIG. 1;
FIG. 5 is a top plan view of the lockable L-handle of FIG.
1.

FIG. 6 is a bottom plan view of the lockable L-handle of
FIG. 1.

FIG. 7 is a right side view of the lockable L-handle of FIG.
1; and,

FIG. 8 is a left side view of the lockable L-handle of FIG.
1.

The broken line showing on FIGS. 4-8 is for illustrative
purposes only and forms no part of the claimed design.
